UNITED STATES PATENT OFFICE.

ROBERT S. LOOKER, OF SPRINGFIELD, OHIO.

SEWING-MACHINE.

SPECIFICATION forming part of Letters Patent No. 349,439, dated September 21, 1886.

Application filed August 1, 1885. Serial No. 173,236. (No model.)

To all whom it may concern:

Be it known that I, ROBERT S. LOOKER, of Springfield, in the county of Clark and State of Ohio, have invented certain Improvements 5 in Sewing-Machines, of which the following is a specification.

In sewing-machines as ordinarily constructed the needle and the presser-foot are attached rigidly to the lower ends of bars which slide 10 vertically to a limited extent in fixed guides. In consequence of this construction it frequently happens that there is difficulty in gaining free access to the feed and shuttle mechanism, that there is difficulty in inserting 15 bulky work below the needle and presser-foot, and that the needle cannot be threaded or adjusted conveniently.

It is the aim of my invention to avoid the difficulties above named; and to this end the 20 invention consists, essentially, in jointing the needle-bar and presser-bar in such manner that the needle and presser-foot may be turned or moved upward above their ordinary positions, so as to afford a high space thereunder 25 and give free access to the various parts.

The essence of the invention consists in the attachment of the presser-foot and of the needle-retaining devices to their respective bars by joints which will admit of their being lifted 30 higher than would otherwise be possible, and it is to be distinctly understood that for this purpose joints of any appropriate character may be employed.

For the purposes of illustration I have represented in the accompanying drawings two 35 forms of joint; but there are many other forms familiar to the skilled mechanic which may be used with equal advantage.

Figure 1 represents a perspective view of 40 the head and a portion of the bed-plate of a sewing-machine having my improvements embodied therein, the presser-foot and needle being shown in their elevated positions. Figs. 2 and 3 are perspective views of a round needle-bar jointed in accordance with my invention, the first-named figure showing the parts as they appear when the needle is turned upward, and the last-named figure the position of the parts when adjusted for operation. Fig. 45 4 is a vertical transverse section through the center of the bar provided with a different form of joint. Fig. 5 is a side elevation of

the same. Fig. 6 is a vertical central section showing a sliding instead of a hinge joint.

Referring to the drawings, A represents the 55 base or bed plate of the machine, and C the head of the usually overhanging arm, which serves, as usual, to support and guide the vertically-reciprocating needle-bar D and the vertically-reciprocating presser-foot bar E. 6a

To the lower end of the bar D, I secure a needle, F, by clamping or fastening devices of any ordinary or approved construction, these devices being foreign to the present invention. At any suitable point above the 65 clamping devices I provide the needle-bar with a joint or hinge of any form or character which will admit of the needle being turned or lifted above its ordinary limit of movement.

In Figs. 1, 4, and 5 I have represented the 70 needle-bar of a flat form, with its lower extremity, b, connected to the upper portion by a shouldered or lapped joint and a pivot-screw, c, this construction permitting the lower end, together with the needle therein, to be turned 75 upward and forward toward the operator, so as to assume a horizontal or approximately horizontal position, as plainly shown in Fig. 1. This position of the parts permits the needle to be conveniently threaded, adjusted, sharpened, or otherwise manipulated, as occasion 8c may require.

In order to lock the jointed ends of the bar and the needle in operative positions, I propose to make use of a fastening device of any 85 suitable character. In the drawings I have represented for the purpose a screw, d, mounted in the needle-bar and arranged to engage a notch in the upper edge of the jointed portion, as plainly shown in Figs. 4 and 5. This fastening-screw has the head recessed or cut away on one side, as shown, so that upon being given a half-revolution it will release the part b and permit the same to swing upon its pivot. 90

In Figs. 2 and 3 I have represented the 95 needle-bar of a round or cylindrical form, the lower extremity being slotted to receive a tenon on the upper portion and secured thereto by a pivot-pin, e, after the manner of an ordinary knuckle-joint. Being thus attached, the lower end, to which the needle is clamped in the ordinary manner, may be turned upward at will at right angles to the upper portion of the bar. In this form of the device I 100

employ as a locking device a rotary sleeve or collar, *e*, mounted on the lower portion of the bar, and provided in one side with a notch or opening, *f*. When the parts are in operative 5 position, the collar is turned so as to throw its notch out of line with the tenon, as shown in Fig. 3, in which position it serves to lock the parts firmly. When the collar is turned in such position as to bring this notch opposite 10 the tenon, the lower end is free to swing upward, the tenon passing through the notch. After being turned upward a rotation of the collar will bring its solid portion opposite the tenon, as shown in Fig. 2, and thus sustain the 15 jointed end and needle in the elevated position.

Instead of joints such as above described, a sliding or telescopic joint, such as represented in Fig. 6, may be employed in connection with a suitable locking device to admit of the needle or presser-foot being lifted bodily above 20 its normal elevation. In this figure it will be seen that the lower portion of the bar is provided with a vertical tenon entering a corresponding hole in the lower portion, and that 25 the two parts are united by means of a spring-locking finger, *f*, and also by means of a set-screw, *g*.

Either of the two joints described may be applied to the needle-bar or to the presser-bar. In order to prevent conflict between the 30 needle and presser-foot when they are swung upward, and for other reasons unnecessary to mention, I prefer to arrange the two, as shown in Fig. 1, to swing in planes at right angles to 35 each other, the needle moving toward the operator and the presser-foot swinging laterally.

By jointing the bars I am enabled to lift the presser-bar and needle to such height as to admit of the hand being passed readily beneath them, so that the shuttle and feed mechanisms may be conveniently adjusted and 40 cleansed, and that fabrics of great thickness may be readily placed in position to be operated upon without injury thereto, and without 45 danger of breaking the needle.

I am aware that a needle-clamping stud has been swiveled in a needle-bar in such manner as to permit the needle to be turned upward, and to such construction I lay no claim. By jointing the needle-bar above the clamp I am 50 enabled to make use of a short and durable needle, and to swing the same upward a great distance above the bed or table. When the needle-clamp is swiveled, a wide space can only be obtained thereunder by the employment of a very long needle, the space in every instance being less than the length of the needle. 55

Having thus described my invention, what I claim is—

1. A sewing-machine having its needle-bar 60 and its presser-foot bar jointed, substantially as described, to permit the needle and presser-foot to be lifted above their operative positions.
2. A sewing-machine having the needle-clamping portion of its needle-bar jointed to 65 turn upward in one direction, and the presser-foot bar jointed to turn upward in a different direction, whereby free access is afforded to the bed of the machine.
3. In a sewing-machine, a needle-bar provided at its lower end with a needle-clamp, and also provided above the clamp with an independent joint, substantially as described, to permit the needle to be lifted above its operative position without releasing its clamp, 70 whereby a space greater than the length of the needle may be secured below the needle-bar.
4. In a sewing-machine, the needle-bar having its lower end hinged to the remaining portion, in combination with the notched rotary 75 sleeve applied thereto, as described, for the double purpose of holding the needle in its operative and in its elevated position.

In testimony whereof I hereunto set my hand in the presence of two attesting witnesses.

ROBERT S. LOOKER.
